[57] ABSTRACT

A device for reducing tubes. Two annular sets of balls are axially spaced in a revolving drawing head and successively engage a tube as it is drawn through the head. The number of balls in one ring is different from that in the other, thereby smoothing out any helical grooves and ridges formed by the first set. The balls are individually mounted in sockets in threaded slugs carrying micrometer markings.

BALL SWAGE FOR REDUCING TUBES
BACKGROUND AND OBJECTS OF THE
INVENTION

Tubes have conventionally been drawn or reduced in size and/or thickness by being pulled through a stationary die. The outer diameter is determined by the diameter of the die, the inner diameter by that of a mandrel supported within the die on a rod which passes through the tube.

The above arrangement produces tremendous friction, with very severe lubrication problems.

A modification of the above involves the replacement of the stationary die by a rotating ring of balls, much like a ball bearing. Such a device is shown in U.S. Pat. No. 1,440,527, granted Jan. 2, 1923, to L. H. Brinkman. This type of apparatus has come to known as a "ball swage." The ball swage greatly reduces the lubrication problems, permitting the use of ordinary machine oil, rather than the exotic lubricants required in the stationary-die machines. However, it introduces problems of its own. Each ball produces a helical groove on the exterior of the tube. Supposedly, successive balls will obliterate the "tracks" of preceding ones, but as drawing speed is increased in relation to the number of revolutions per minute of the drawing head, that is not always the case and the surface of the tube has a slight ripple which may exceed allowable tolerances, particularly in high precision work. This is most likely to occur in the case of relatively large tubes, for example those three inches or more in diameter. The effect is less pronounced when the ball swage includes two rings of balls rotating in opposite directions as shown in U. S. Pat. No. 1,414,500, granted to L. H. Brinkman on May 20, 1922. This arrangement, however, complicates the drive.

Another problem in connection with the ball swage is the rapid wear on the balls, which make point contact with the drive mechanism. The Brinkman U.S. Pat. No. 1,440,527 referred to above seeks to minimize this by elaborate means for producing a complicated rotational movement of the individual balls to equalize the wear.

Another defect of known ball swages is the limited range of tube sizes which can be handled by any one rotor.

Accordingly, one object of my invention is to provide a ball swage which will eliminate or reduce the ripple effect produced by prior devices without necessarily employing oppositely rotating ball dies.

Another object is to provide a ball swage in which the balls make surface contact with the driving means to reduce the wear on the balls.

Another object is to provide a means for accurately controlling the outer diameter of the tube.

Another object is to provide a ball swage having a wide range of adjustability, enabling it to handle tubes of many different sizes.

THE DRAWINGS

In the drawings,
FIG. 1 shows diagrammatically the general arrangement of the ball swage.

FIG. 2 shows a partial longitudinal section of the rotary drawing head and associated parts.

FIG. 3 is a section on line 3—3 of FIG. 2 on a reduced scale and in a simplified representation, showing one set of balls.

FIG. 4 is a section on line 4—4 of FIG. 2 on a reduced scale and in a simplified representation, showing the other set of balls.

FIG. 5 is a top plan view of one of the plugs 21, 21', of FIGS. 2, 3, and 4, including a surrounding portion of rotor body 20.

FIG. 6 is a longitudinal sectional view of a modified form of one of the plugs 21, 21'.

SUMMARY OF THE INVENTION

My invention involves the use in a ball swage of two rotating annular sets, or rings, of balls rotated in the same direction and at the same speed. Preferably, though not necessarily, they are mounted in a single rotor. The number of balls in the two sets are different so that the relationship of the helical paths produced by individual balls in one set will be different from the relationship of the paths produced by the balls of the other set. Preferably, the numbers of balls in the two sets should have no common integral divisor except "one." For example, if there are eight balls in one set there may be five or seven in the other.

In order to reduce and equalize the wear on the balls and provide for their adjustment, I mount the balls in hemispherical sockets formed in individual threaded 30 plugs. These plugs have micrometer markings on their outer ends and are capable of adjustment over a considerable range, say 1 inch or more.

DETAILED DESCRIPTION

Referring to FIG. 1, 1 represents the frame or support, normally part of a conventional draw bench, such as is shown, for example, in the right-hand portion of FIG. 1 of Brinkman's U. S. Pat. No. 1,414,500. Rotary die or drawing head 3 is mounted for rotation in ball or roller bearings 5. It is shown as provided with a V-belt pulley 7, but may be driven by any suitable means, such as a gear train. The rotary die 3 includes two annular sets of balls 9, 9', which engage the tube 11 which is to be reduced. Within the tube is a plug or mandrel 13, carried by rod 15, which in turn is swiveled by ball-joint 16 on any suitable support 17. The tube is drawn through the die by gripper 19 which is attached to the pulling mechanism of the draw bench (not shown).

Reference is now made to FIGS. 2, 3, and 4 where the details of rotary die 3 and its mounting are shown. The frame 1 carries a fixed sleeve 2. Rotor 3 is journaled in a removable sleeve 4 by roller or ball bearings 5. In use, sleeves 2 and 4 are locked together by a stud

55 10 or other locking means which can be disengaged to permit movement of sleeve 4. Sleeves 2 and 4 are provided with apertures 6 and 8, respectively. In normal use, they are non-aligned, as shown in FIGS. 3 and 4. After disengagement of stud 10, sleeve 4 can be rotated 60 to cause them to match up, providing access to rotor 3 for a purpose to be explained later. Rotary die 3 includes a rotor body 20 having an accurately machined inner surface 22, a portion of which is frusto-conical. Threaded plugs 21, 21' are mounted in two annular sets. (The parts of one set are indicated throughout by the primed reference characters.) The plugs are shown as made of steel with bearing blocks 23, 23' of alu-

minum bronze, which are sweated or threaded in the plug body. Alternatively, the entire plug may be made of aluminum bronze. The balls 9, 9' are held in hemispherical cavities, in which they rotate freely, in bearing blocks 23, 23' by retainers 25, 25' which are threaded on plugs 21, 21'. Felt pads 27, 27', held by tabs 29, 29' on retainers 25, 25', serve to lubricate and clean balls 9, 9'. Grooves 31, 31', which will be discussed in more detail later, carry lubricant, by centrifugal force, along the plugs for cooling purposes. The lubricant is squirted into the interior of the rotor from the left-hand end in considerable quantities, conveyed by the frustoconical surface 22, and serves to lubricate and cool the tube 11, the balls 9, 9' and the rotor body 20.

Referring to FIGS. 3 and 4, it will be noted that there are eight plugs 21 and associated balls 9 and five plugs 21' and associated balls 9'. Hence, balls 9' will not follow the tracks of balls 9 and will tend to smooth out grooves and ripples. It may be found desirable, however, to slightly adjust the drawing speed since it is possible under specific ratios of drawing speed and rate of rotation of the rotary die, for one ball 9' to follow the track of one ball 9.

While I have shown the balls 9, 9' as having the same diameter, they may be of considerably different size, the balls 9' being preferably the larger. Under some conditions, this aids in the smoothing action.

The adjustment of plugs 21, 21' will now be described. The sleeve 4 is unlocked from sleeve 2 and rotated to align apertures 6 and 8, giving access to the outer ends of the plugs. The plugs are threaded at 33, 33' with the pitch being such as to provide a convenient micrometer relationship. If English units are to be used, forty threads per inch is a convenient value. Referring to FIG. 5, it will be noted that the plug 21 has its circumference marked by 25 evenly spaced indices 34, while rotor body carries a single index mark, 35. Thus each division on the plug indicates a movement of 0.001 inch when the plug is turned.

In the periphery of each plug there are five grooves 31 and in the rotor body there are five grooves 37. Matching of a groove 31 with a groove 37 permits insertion of a locking pin. The grooves 37 are evenly spaced about the axis of the plug, but the spacing of grooves 31 varies. For example, they may be located at "zero," "four," "six," "12," and "18." The principle is similar to that of a vernier. With this arrangement, whenever one of the indices on plug 31 is aligned with index 35, a groove 31 will be aligned with a groove 37 and a locking pin (not shown) may be inserted to fix the plug 31 in place. The essential characteristic of the spacing of grooves 31 is that the variations in spacing of the grooves are integral multiples of the spacing of the indices. It is desirable to provide swingable tabs 39 which may be turned to cover the matched grooves 31-37 to prevent the locking pin from being thrown out by centrifugal force. Sockets 41 provide for insertion of a tool to turn the plugs 21. A removable cover plate 43 forming part of frame 1 provides access. Oil thrown out into the space between rotor 20 and cylinder 4 drains away through a hole (not shown).

In FIG. 6 I have shown a modified form of plug 121. The bronze bearing block 123 carries the ball 109 held in a hemispherical cavity by retainers 125 on which felt pads 127 are secured.

It will be noted that in this modification, the bearing block forms an extension of the plug. By having in stock plugs of the forms shown in FIG. 6, in addition to those shown in FIG. 2, the operator can work tubes in a wide variety of sizes, since the individual plugs are adjustable over a range of an inch or more.

OPERATION

The tube is pulled between mandrel 13 and rotary die 3 by gripper 19. The tube is thinned and lengthened because of the cooperative action of balls 21, 21' and mandrel 13. Because of the two sets of balls 21, 21' and because there is a different number of balls in each set, a particularly smooth finish is produced.

In order to accurately determine the exterior diameter of the tube, the operator proceeds as follows. A stepped plug guage is provided. The larger portion fits in surface 22, thus centering the guage on the axis of rotation of the die. The smaller portion has an accurately known diameter approximating the desired external diameter of the finished tube. Plugs 21, 21' are screwed in until balls 9, 9' touch the surface of the plug guage. Using the micrometer markings, the operator then advances or retracts the necessary amount to give the desired diameter tube.

While I have described a specific embodiment of my invention, it will be apparent that various changes can be made. For example, while the two annular sets of balls are, in my preferred embodiment, mounted in the same rotor, they could, if desired, be mounted in separate rotors rotated in the same direction and at the same speed.

Moreover, while one rotary die of the type I have shown produces very smooth metal, it may be desirable for even greater smoothness or for other purposes, e.g., to eliminate torsional stresses in the tube, to utilize two such dies in tandem rotating in opposite directions.

I therefore wish my invention to be limited only by the scope of the appended claims.

The embodiments of the invention in which an exclusive property or privilege is claimed are defined as follows:

1. In a tube drawing apparatus comprising a mandrel adapted to support a tube from its inside, die means arranged to surround said mandrel and engage said tube and means for drawing said tube between said mandrel and said die means, the improvement wherein said die means comprises at least a first and a second annular set of substantially evenly spaced freely rotatable balls adapted to form a die and engage said tube, and means for rotating said sets of balls about the axis of said tube in the same direction at the same rotational speed, the number of balls in one of said sets being different from the number of balls in the other set, whereby the balls of the second set will tend to smooth out any ripples on the outer surface of the tube formed by the first set.

2. A tube drawing apparatus as defined in claim 1 wherein said two sets of balls are mounted in a single rotor.

3. In a tube drawing apparatus comprising a smoothly cylindrical mandrel adapted to support a tube from its inside, a rotary die means comprising a rotor body annular in cross section surrounding and coaxial with said mandrel carrying balls arranged to engage said tube, means for drawing said tube between said mandrel and said die means, and means for rotating

said rotor about its axis, the improvement wherein said rotary die means comprises:

- a. a first annular set of radial plugs in said rotor body surrounding said axis, said plugs being threaded in said rotor body, each plug having a substantially hemispherical socket in its radially inner end, a ball mounted in, and free to rotate in, each socket, and retaining means for retaining the balls in the sockets, said balls projecting radially inwardly beyond the inner surface of said rotor body, and
- b. a second annular set of plugs and associated balls in said rotor body of substantially the same form and arrangement as said first set of plugs and balls, the number of plugs in said second set being different from the number in said first set.

4. A rotary die for drawing tubes comprising a rotor body annular in cross section, mounted for rotation about its axis, an annular set of radial plugs in said rotor body surrounding said axis, said plugs being threaded in said rotor body, each plug having a substantially hemispherical socket in its radially inner end, a ball mounted in, and free to rotate in, each socket, and retaining means for retaining the balls in the sockets, said balls projecting radially inwardly beyond the inner surface of said rotor body, indicia on the outer end of each of said plugs, an index marking on said rotor body

adjacent each of said plugs and corresponding sets of grooves in said plug and said rotor body, the grooves extending longitudinally of said plugs, the grooves in one member being evenly spaced and the grooves in the other member having a different spacing, the variations being multiples of the spacing of the indices, whereby, when any one of said indicia is aligned with said index marking, a groove in said plug will be aligned with a groove in said rotor body and said plug may be locked in position by insertion of a pin.

5. A device as defined in claim 4, wherein said grooves extend the entire length of said plugs, thereby serving as cooling means.

6. A device as defined in claim 3 and further comprising pads attached to said retaining means and serving to clean and lubricate said balls.

7. A device as defined in claim 1 wherein the numbers of balls in the two sets have no integral common divisor other than unity.

8. A device as defined in claim 3 wherein the number of balls in the two sets have no integral common divisor other than unity.

9. A device as defined in Claim 1 wherein the individual balls of the second set are larger in diameter than the individual balls of the first set.
